UNITED STATES PATENT OFFICE.

RICHARD ATWATER, OF MERIDEN, CONNECTICUT.

PRINTER'S QUOIN.

SPECIFICATION forming part of Letters Patent No. 340,475, dated April 20, 1886.

Application filed May 26, 1885. Serial No. 166,710. (No model.)

To all whom it may concern:

Be it known that I, RICHARD ATWATER, of Meriden, in the county of New Haven and State of Connecticut, have invented a new and 5 useful Improvement in Printers' Quoins; and I hereby declare the following to be a full and clear description of the same.

The object of this invention is to construct a quoin in three pieces—viz., a sliding way, a 10 wedge, and a follower, the whole united by a transverse rod or rivet in such a manner as to allow the wedge to slide longitudinally between its sliding way and the follower, and thus tighten the quoin in place in the chase, the 15 quoin being provided with a cogged rack and a pinioned key for moving the wedge in its seat between the way-piece and the follower, thereby obviating the necessity of striking the wedge and hammering it into place.

20 The details and nature of the invention will be readily understood by the subjoined description, and by the accompanying drawings, of which—

Figure 1 is a plan of the improved quoin in 25 its closed position. Fig. 2 is a plan of the quoin in its open position. Figs. 3, 4, and 5 are respectively plans of the edges of the three 30 separate and respective pieces of which the quoin is composed. In these detached views the edges of the said pieces are shown in the same positions in which they are shown in Figs. 1 and 2. Fig. 6 is a face view of the inside of the way-piece, and showing its cogged rack. Fig. 7 is a plan of the transverse face 35 of the wedge-piece. Fig. 8 is a plan of the inner face of the follower-piece. Fig. 9 is a transverse section of the whole quoin, taken through the assembling-rivet, on the line $x-x$ of Fig. 1. Figs. 10 and 11 are respectively a 40 plan and end elevation of the key for tightening the wedge.

The quoin is composed of three pieces, A, B, and C. The piece A is the sliding way-piece, and is of the same width at both its ends. The 45 piece B is the wedge-piece, and of course it is made thicker at one end than the other. The piece C is the follower, and it is, like the wedge, made thicker at one end than the other, so that when the whole of these three parts are 50 assembled together, as in Figs. 1 and 2, the

exterior faces of the way-piece A and the follower-piece C are nearly or quite parallel.

The interior face of the way-piece is provided with a cogged rack, a , as shown in Figs. 3 and 6. It also has near its forward end an inwardly-projecting lug, a' , as is also shown in said Figs. 3 and 6.

The wedge-piece B has its central part excavated, so as to form a transverse slot or mortise, b , which extends quite through the said piece for nearly its entire length, as is shown in Fig. 7. Near the wider end of the said wedge-piece it has a transverse chamber or cavity, b' , of semi-cylindrical formation, extending nearly across its face, which is placed next the cogged rack of the way-piece. A turning key or winch, D, has its lower end made in the form of a cogged pinion, d , which is adapted to enter the cavity or chamber b' , and be thereby held in place relatively to the other parts, and while therein seated to engage with the teeth of the cogged rack a , so that by rotating the said key or winch by means of its handles $d' d''$ the wedge-piece B is shoved or moved forward on its sliding way- 75 and between it and the follower C. The follower C is also made in a wedge-shaped form, as shown in Figs. 1, 2, and 5, and it, like the piece A, has an inwardly-projecting lug on its inner face and near its wider end. This lug c , 80 as well as the before-mentioned lug a' , is adapted to enter the slot b of the wedge-piece, and by those lugs and the central mortise, b , in which they engage, serves to hold the three pieces laterally in their relative positions each to 85 the other at that point. An assembling pin or rivet, E, passes through the three pieces A B C at the central part of the lug c and holds the three said pieces together. This rivet or pin is not riveted up tightly to the parts A 90 and C, but its head is placed in a deeply-sunk countersink or cavity, c' , in the outer face of the piece C, and so loosely holds the parts together, as shown in Fig. 9, thus permitting a full stroke of the wedge-piece B, and a consequent separation of the pieces A and C. 95

By putting the key or winch in its seat b' , with its toothed or pinioned end in the teeth of the rack a , and turning the said key or winch, it rolls ahead or back, as the case may be, on 100

the said cogged rack, and thus pushes the wedge ahead between its way-piece and the follower, or draws the wedge back, and thus the quoin is tightened or loosened in its place 5 in the chase.

Having thus described my invention, what I claim as new, and desire to secure by Letters Patent, is—

1. A quoin formed of a straight way-piece, with a cogged rack on its interior face, a wedge chambered transversely for nearly its entire length, and a tapering follower-piece, the whole held in proper relative position each to the other by means of inwardly-projecting lugs on the adjacent faces of the two outer pieces and the central slot of the intervening wedge-piece, into which the said lugs engage, the whole held together by a transverse rivet or bar, which holds the parts loosely together, substantially as shown and set forth.

2. The parallel-sided way-piece A, cogged on its interior face, and also provided with an inwardly-projecting lug, a' , near one of its ends on the same face, the tapering follower-

piece C, with a similar lug, c , near its wider 25 end, and the central wedge, B, chambered for nearly its entire length, for the longitudinal movement therein of the said interlocking lugs a' and c , the whole combined as described and set forth.

3. In a quoin, a sliding wedge seated between a parallel-sided sliding way and a tapering follower-block, the way-piece and the follower attached together by a connecting bar or rivet, which passes through a central longitudinal slot in the wedge, said quoin being adapted to be operated by a turning key or winch fitted into an aperture or notch in the wedge, and arranged to engage with a cogged rack on the way-piece, substantially as shown 35 40 and set forth.

In witness whereof I have hereunto set my hand this 18th day of May, 1885.

RICHARD A TWATER.

In presence of—

FREDERICK HOPKINS,
WILLIAM B. PATTEN.
